APPARATUS FOR MOUNTING SAFETY PINS
ON CARDS

Harry Alfandre, Jamaica, N. Y.

Application November 1, 1943, Serial No. 508,471

24 Claims. (Cl. 163—8)

This invention relates to apparatus for mounting safety pins on cards or other pin carriers formed of sheet material. This application is a continuation-in-part of my application Ser. No. 476,593, filed in the United States Patent Office on February 20, 1943.

The primary object of the present invention is the provision of an apparatus by which the mounting of safety pins on cards is greatly facilitated and expedited. In other words, the main purpose of the present invention is to provide an apparatus which eliminates the tedious, slow and inefficient operations heretofore necessitated in the method practiced for a great many years in the mounting of safety pins on cards. More specifically, the main objects of the present invention are: to facilitate the opening of safety pins; to facilitate the assembly of the pins with the card on which they are mounted; and to facilitate the closure of the pins after the prongs thereof are passed through said card in assembling the pins thereon.

Another prime object of the invention is to provide automatically operable apparatus for assembling the pins on the cards and for closing the pins after they are mounted on the cards.

The above objects of the invention and other objects ancillary thereto will best be understood from the following description of the apparatus embodying the present invention, reference being had to the accompanying drawings which are to be considered as illustrative of the invention and not limitative thereof.

In the drawings:

Fig. 1 is a top plan view of apparatus embodying the present invention;

Fig. 2 is a sectional view on the line 2—2 of Fig. 1;

Fig. 3 is an end view taken on the line 3—3 of Fig. 1;

Fig. 4 is a sectional view on the line 4—4 of Fig. 2;

Fig. 5 is a front view, with parts in section, of a part of the apparatus, illustrating the operation of the pin opening means;

Fig. 6 is a vertical sectional view of part of the apparatus, illustrating the pin-closing operation after the pins are applied on the card;

Fig. 7 is a front view of the apparatus;

Fig. 8 is a plan view of a card with the safety pins mounted thereon;

Fig. 9 is a top plan view of part of the pin holder;

Fig. 10 is a side view of the part shown in Fig. 9;

Fig. 11 is a top plan view of automatically operable apparatus embodying the present invention, parts being broken away for the purpose of illustration;

5 Fig. 12 is a front view in elevation, partly in section, of the apparatus illustrated in Fig. 11;

Fig. 12A is a side view of part of the apparatus as seen from the line 12A—12A in Fig. 12;

Fig. 13 is a top plan view of part of the pin holder shown in Fig. 11;

Fig. 14 is a sectional view on the line 14—14 of Fig. 13;

Fig. 15 is a sectional view on the line 15—15 of Fig. 13;

15 Fig. 16 is a top plan view of part of the pin-carrier holder shown in Fig. 11;

Fig. 17 is a sectional view on the line 17—17 of Fig. 16;

Fig. 18 is a fragmentary view of the pin-carrier holder as viewed from the left in Fig. 11;

Fig. 19 is a fragmentary side view of the pin-carrier holder as viewed from the right in Fig. 11;

Fig. 20 is a view of part of the apparatus as it appears when observed from the line 20—20 in 25 Fig. 12;

Fig. 20A is a front view of a cam forming a part of the apparatus;

Fig. 21 is a sectional view on the line 21—21 of Fig. 20;

30 Fig. 22 is a bottom view of part of the mechanism illustrated in Figs. 20 and 21;

Fig. 23 is a sectional view on the line 23—23 of Fig. 21;

Fig. 24 is a perspective view of a part of the mechanism illustrated in Fig. 21;

Fig. 25 is a perspective view, on a larger scale, of part of the mechanism illustrated in Fig. 20;

35 Figs. 26 to 35, inclusive, are views illustrating more or less diagrammatically the operation of the apparatus.

Referring first to Fig. 8, there is shown a pin carrier such as, for example, card C which has mounted thereon a plurality of safety pins P. One of the pins has been omitted from the illustrated card to show one pair of a plurality of pairs of apertures a through which the prongs of the pins extend, there being as many pairs of apertures as pins which are mounted on the card. Usually, in accordance with the prior art practice, the cards are provided with these apertures before the pins are applied thereto, in order to make it easier to pass the prongs of the pins through the card. In applying safety pins to cards by means of the apparatus of the present invention, however, the provision of these

apertures in the cards is unnecessary, but is optional as the present apparatus can be used for applying safety pins to cards whether or not the latter are provided with prong receiving apertures. It will be understood that in mounting safety pins on cards, it is necessary first to open said pins, since the pins, as manufactured, are closed; then the open pins must be assembled in proper spaced relation on the cards; and thereafter the pins on the cards must be closed.

Although in the presently preferred embodiment of the invention, the apparatus is automatically operable to mount the pins on the cards and to close the pins after they are assembled with the cards, the manually operable apparatus embodying the invention will be described first and then the automatically operable apparatus will be described.

Referring now to the manually operable apparatus of the present invention, said apparatus comprises a card holder 10 in which the card C is mounted in condition to permit the safety pins to be passed therethrough. More particularly, as illustrated in Fig. 2 the card C is bent substantially into the form shown, providing in the card an intermediate arched or curved portion 12 for the passage of each prong of the pins through a pair of apertures a or through corresponding parts of the card when the latter is not provided with apertures. The card holder 10 comprises a longitudinally extending stationary forming member 14 provided with a convexly curved upper surface 16 corresponding to the contour to which the intermediate part 12 of the card is to conform and having opposite flat parallel sides 18 and 20. The upper surface of member 14 is provided with a plurality of parallel transverse grooves 22 spaced from each other longitudinally of member 14. The number of grooves 22 is equal to the maximum number of pins to be mounted on the card and it will be understood that the prongs of the pins are passed through said grooves for predetermining the spacing of the pins laterally of each other on the card. Further, it will be understood that when the cards are provided with the apertures a, the apertures of each pair are in alignment with the opposite ends, respectively, of a companion groove 22. The card is held in the card holder 10 by the movable card retaining member 24 which comprises the side bars 26 and 28 pivotally mounted at their rear ends to the pivot pin 30 which is secured to member 14. Said bars 26 and 28 straddle member 14 and are connected to each other at their front ends by the spacing and handle member 32 to which said side bars are secured in any suitable way as by screws 34. Side bar 26 is provided with a longitudinally extending part 36 of increased thickness and having in the upper edge thereof a plurality of grooves 38 in alignment with grooves 22, respectively, of member 14. The upper edge of bar 28 is also provided with grooves 40 which are in alignment with the grooves 22 of member 14.

By reference to Fig. 2 it will be noted that before the prong of the safety pin is passed through the card C in the card holder 10, the end of the prong rests in a groove 38 on the upper edge on the part 36 of side bar 26. As the prongs of safety pins of the same over-all size vary in length, the upper grooved edge of part 36 is thick enough to be engaged by the shorter as well as by the longer prongs when the pins are in the position illustrated in Fig. 2 preliminary to the projection of the prongs through the card C in

the holder. The card holder 10 is provided with a slot forming strip 42 which is secured to side 18 of member 14 and is spaced from said side 18 by an amount substantially equal to the thickness of the card C (Fig. 2). A gauge strip 44 is disposed between strip 42 and side 18 of member 14 below the upper edge of strip 42, providing a gauge slot in which one side edge portion of the card is received, whereby to predetermine the location of the bent intermediate portion 12 of the card in the proper region thereof for the attachment of the pins thereto. The forward end portion of strip 42 is bent around the front end of member 14, as indicated at 46 in Fig. 1, to provide a gauge-stop for one end of the card to aid the operator of the apparatus in positioning the card longitudinally of member 14 in the card holder.

It will be understood that when a card is to be placed in the card holder 10, the movable member 24 is raised clear of its engagement with the sides 18 and 20 of member 14 to permit one side edge portion of the card to be inserted in the slot between strip 42 and the adjacent side 18 of member 14, with the edge of the card in engagement with the upper edge of gauge strip 44, and with one end of the card against the end gauge portion 46 of strip 42. Then, movable member 24 is lowered to the position illustrated in Fig. 2 thereby bending the card into the form illustrated and holding longitudinally extending portion of the card against the adjacent sides 18 and 20 of member 14. As thus contoured and positioned, the card is in condition to have the pins projected therethrough. The means for accomplishing this will now be described.

It will be understood by those familiar with the art of manufacturing safety pins and mounting them on cards that when the safety pins are manufactured, they are closed, that is, the prongs are engaged in the heads of the pins, the pins being usually delivered in this condition for finishing or other operations which must be performed in the pins after they are manufactured in the pin-making machine, and that it is therefore necessary, of course, to open the pins before they can be mounted on the cards. It is also well understood by those familiar with this art that the operation of opening pins is slow and tedious and involves a serious occupational hazard to the individuals who have the job of performing this operation. The present invention makes provision for obviating the disadvantages of the old method of opening the safety pins. In the preferred form of the apparatus illustrated herein, this result is accomplished by means which includes a part of the means for projecting the pins through the card in the card holder 10, but it will be understood that this means for projecting the pins through the card holder 10 can be used without utilizing the pin opening feature thereof.

The means provided in the present apparatus for facilitating the opening of the pins and for projecting the pins through the card in the card holder 10 comprises a pin holder 48 secured to a shaft 50 which is journaled for turning movement in brackets 52 fixed to a cross bar 54 in any suitable way as by screws 56 (Fig. 4). Said cross bar is mounted on a slidable plate 58 to which it is pivotally secured by a shouldered pivot screw 60. Plate 58 is slidable on a flat metal plate 62 mounted on top of a table or bench 64 and is guided for rectilinear movement transversely of the card holder 10 by the guide rails 66 which are secured

to plate 58. Said plate 58 is movable from the position illustrated in Fig. 2 to the position illustrated in Fig. 6 by depressing the pedal 68 (Fig. 7) to which a cord or chain 70 is connected, said cord passing over a pulley 72 and being secured to a lug 74 which is fixed to plate 58. When pedal 68 is released, plate 58 is retracted by springs 76 which are secured at their opposite ends to lugs 78 and 80 fixed to plate 58 and to plate 62, respectively. Stop pins 82 are provided for limiting the movement of plate 58 in one direction and stop pins 84 are provided for limiting movement of said plate in the opposite direction.

Referring now more particularly to the pin holder 48 which is pivotally mounted in frame brackets 52 by means of the shaft 50, said pin holder comprises a plate 86 provided with a plurality of pin retaining members, each having end parts 88 and 90 in which the spring and head ends, respectively, of a safety pin are received, with the prong *Pr* and the side wire *Pw* of the pin in a vertical plane and with the prong of the pin on top. As shown more clearly in Figs. 1, 9 and 10, the end part 90 of each pin retaining member on the pin holder 48 has a short side 92 which permits the prong of the pin to be moved laterally out of engagement with the head of the pin for opening the pin. Lateral movement of the pin as a whole in the pin retaining member is prevented by said side 92 and the opposite side 94 of end part 90, and by the side parts 96 and 98 of end part 88. Also, a lug 99 offset inwardly from part 92 and positioned near end part 90 is engageable with the side *Pw* of the pin near the head of the pin for assisting in preventing lateral movement of said side wire during the opening of the prong *Pr* of the pin. When the pin is in the retaining member of the pin holder, the spring end thereof engages the part 100 between the side parts 96 and 98 at the end part 90. The pin holder is provided with a combined post and handle member 102 which is integral with or in fixed relation to plate 86. Said member 102 has a bevelled end 104 which engages the top of plate 58 for supporting the pin holder at the proper angle when said pin holder is positioned to receive the pins as illustrated in Fig. 2 and for engagement by the prong releasing member 106 of the pin opening device as illustrated in Fig. 5.

The pin opening member 106 is constituted, as here shown, by a flat bar provided with a plurality of notches in one edge thereof, each of said notches being defined by an edge portion 108 extending substantially at right angles to the edge of the bar and by an edge portion 110 inclined from the inner end of edge portion 108 to the edge of the bar. It will be understood that there is a notch for each pin which is to be opened and that said notches are in alignment with the pin retaining members, respectively, and extend longitudinally of said bar to the spaces between the pin retaining members of the pin holder. Accordingly, when the prong releasing bar 106 is moved to the position illustrated in Fig. 5 for disengaging the prong from the head of the pin, the inclined edge portion 110 of the corresponding notch of the bar forces the prong of the pin downwardly and laterally over member 88 into the space between two adjacent pin retaining members, the lateral movement of said prong being limited by the edge portion 108 of the notch, and when the prong releasing bar 106 is moved to its retracted position, the prongs of all of the pins in the pin holder 48 are moved upwardly by the springs of the pins so that

they point upwardly as illustrated in dotted lines in Fig. 5.

The means for operating pin releasing bar 106 comprises a crank arm 112 to which the rear end 5 of bar 106 is rigidly secured. Said crank arm is fixed to a shaft 114 journaled for turning movement in a bearing 116. Said bearing has a rigid 10 base 118 which is rigidly secured at the proper height above plate 58 by means of tubular posts 120 which are bolted to plate 62. Shaft 114 is rotated by a sprocket wheel 122 which is fixed thereto and which is engaged by a sprocket chain 124. Said sprocket chain passes over said sprocket wheel and downwardly through openings 126 in plate 62 and in the top of table 64. One end of said sprocket chain is connected by means of a cord or chain 128 to a treadle 130 and the other end of said sprocket chain is connected to one end of a spring 132, the other end 20 of said spring being secured to a fixed eyebolt or the like 134. Accordingly, when treadle 130 is depressed, sprocket wheel 122 is rotated in a clockwise direction viewing Figs. 2, 5 and 7, and the pin releasing bar 106 is moved from its retracted position illustrated in Figs. 2 and 7 to the projected position illustrated in Fig. 5 for releasing the prongs from the pins mounted in holder 48. Immediately thereafter upon release 25 of treadle 130, the spring 132 pulling on sprocket chain 124 rotates shaft 114 in a counter-clockwise direction, thereby moving the prong releasing bar 106 to its retracted position and allowing the prongs of the pins to move upwardly in the spaces between the adjacent pin retaining members substantially to the position illustrated 30 in dotted lines in Fig. 5.

After the pins are thus opened, they are of course in condition to be projected through the card on which they are to be mounted, but before they can be projected through the card, the pin holder 48 must be moved to the intermediate position thereof illustrated in dotted lines in Fig. 40 2 for disposing the prongs of the pins below the side wires thereof in engagement with the grooves 38 of side bar portion 36 of the card holder 10 in which position the prongs point toward the card in the card holder and are aligned with the grooves 22 in member 14 of the card holder and with the companion pairs of apertures *a*, when 45 the card is provided with such apertures. The pin holder is moved to this intermediate position by turning the same quickly about the axis of shaft 50, thus to prevent the pins from falling out of the holder. It will be understood that the pins remain in position in the holder during the movement of the latter from a vertical position in moving from the position of the holder shown in full lines in Fig. 2 to the position of the holder shown in dotted lines in Fig. 2, by reason of the 50 inertia of the pins which operates to keep the pins in the holder while the latter is moved from its vertical position to said last mentioned position thereof. For turning the holder the front end of shaft 50 is provided with a handle 136 which, when turned quickly in a clockwise direction, viewing Fig. 2, moves the pin holder and the opened pins carried thereby to the position illustrated in dotted lines in said figure of the drawings. It will be noted by reference to Fig. 2 55 that the pivotal axis of holder 48 extends parallel to and is spaced laterally of a line extending through the receptacle ends 88 in which the spring ends of the pins are received whereby said ends of the receptacles are eccentric to said pivotal axis, and that the pin holder 48 is movable 60

from the pin-receiving and pin-opening position in which the receptacle ends 88 are disposed at one side of said pivotal axis to a position toward the card in which said receptacle ends 88 are disposed at the opposite side of said pivotal axis, 5 said last mentioned position being illustrated in dotted lines in Fig. 2. The prongs of the pins are thus properly positioned for movement through the slots of the card holder. The pin holder and the pins carried thereby are then 10 moved to the right viewing Fig. 2 by depressing treadle 68 and during this movement the prongs of the pins are projected through the cards, the prongs passing below or at the concave surface of the intermediate arched portion 12 of the card and the head and side wire of the pin passing over the other side of said arched portion of the card. While the holder 48 and the pins carried thereby are thus being moved by the operation 15 of treadle 68, the handle 102 of the pin holder 48 is grasped by the operator of the apparatus and pressure is exerted downwardly on the holder 48 so that the pin prongs are held down in engagement with the bottoms of the grooves 38, 22 and 40. At the end of the movement of holder 48 to the right at which time the ends of the prongs of the pins project laterally beyond side bar 28, the holder 48 is further depressed by the operator and at the same time the holder is turned on its pivot 60 for moving the heads of the pins laterally of the pointed ends of the prongs and sufficiently below said prongs to allow the ends of said prongs to move into said heads, thus closing the pins as illustrated in Fig. 6. Then the holder 48 is returned to its pin receiving position and substantially simultaneously the treadle 68 is released whereby the pin holder is returned by springs 76 to the retracted and spring receiving position illustrated in full lines in Fig. 2. Finally the card with the pins mounted thereon is removed from the card holder.

It will be clearly understood from the above description that in the use of the above described apparatus, a plurality of pins are simultaneously opened by operation of the pin releasing bar 106 and that the opened pins are simultaneously projected through the card on which the pins are to be mounted, said card being positioned on the card holder 10, and that after said pins are projected through said card in the card holder, they are simultaneously closed by depressing and slightly turning the pin holder 48 about its pivot 60. It will be understood, however, that while the pin releasing bar and the mechanism for operating the same for opening the pins is preferred and cooperates with the pin holder 48 which thus constitutes part of the pin opening means of the present invention, as well as part of the means for projecting the pins through the card in the card holder, it is not absolutely essential although highly desirable, to use the pin opening means as part of the apparatus for attaching the pins to the cards, and likewise it will be understood that the part of the apparatus which is utilized for opening the pins could be used for this purpose without utilizing the part of the apparatus for projecting the pins through the cards. Accordingly, it will be understood that since the apparatus involves parts which have utility apart from each other, although their greatest utility lies in their conjunctive use, I wish to claim not only the combination of these parts with each other, but also these parts separately.

Referring now to the automatically operable apparatus illustrated in Figs. 11 to 35, this appa-

ratus includes a prong-releasing member 106 like that provided in the manually operable apparatus illustrated in Figs. 1 to 10, said prong-releasing member being operated by the treadle 130 and the retracting spring 132 connected to the opposite ends of the sprocket chain 124, as hereinbefore described. The pin holder 48A which will be presently described in detail holds the pins substantially in the same way as the pin holder 48 for action thereon by the prong-releasing member 106, and it will be understood that so far as opening the prongs of the pins is concerned, pin holder 48A and prong-releasing member 106 are related to each other in the same way as hereinbefore described with reference to the apparatus illustrated in Figs. 1 to 10.

Referring now more particularly to the pin holder 48A, the latter is preferably of the construction illustrated in Figs. 11 to 15 and as shown comprises a metal casting 150 provided with a plurality of laterally spaced pin receptacles 152 each having a groove 154, in the bottom or inner end thereof, for receiving the side wire of the safety pin in the companion receptacle, and end recesses 156 and 158 for receiving the spring end and head end, respectively, of said pin. Recess 158 is continuous with an opening 160 which allows the prong of the pin to be moved laterally of the head thereof for disengagement of said prong from said head by the prong-releasing member 106 substantially in the same way as described above with reference to the apparatus illustrated in Figs. 1 to 10, and for engagement of said prong with the head of the pin after the prong is projected through the pin carrier C in the card holder 10A. Pin holder 48A is provided with an end portion 162 which is mounted on a pin 164 carried by brackets 166 which are fixed to and upstand from the slidable plate 168. Pin 164 passes through a longitudinal bore 170 (Fig. 14) formed in said end 162 of pin holder 48A. As illustrated in Fig. 11, a spring 172 is disposed between one of the brackets 164 and the adjacent side of the pin holder 48A. Thus, it will be understood that pin holder 48A is mounted for pivotal movement on pin 164 and for movement longitudinally of said pin, that spring 172 resiliently opposes movement of said pin holder longitudinally of said pin in one direction, and that said spring is operable to move said pin holder in the opposite direction after movement of said pin holder longitudinally of said pin in said first mentioned direction. The movement of pin holder 48 longitudinally of pin 164 is utilized in lieu of the pivotal movement provided by the pivot pin 60 in the case of pin holder 48, for closing the pins after the prongs thereof are projected through the card or pin carrier C as illustrated in Fig. 6.

The pin holder 48A is movable with slidable plate 168 toward and away from the pin carrier holder 10A, for projecting the prongs of the pins through the card or pin carrier mounted in said holder, and it will be understood from the above description of the apparatus illustrated in Figs. 1 to 10 that before the pin holder is moved toward the pin carrier or card holder, said pin holder is pivotally moved from an upright or pin-receiving position in which the open prongs of the pins are above the companion side wires of the pins, to an inverted position in which said prongs are below said side wires, as diagrammatically illustrated in Figs. 28 and 29, respectively. The pin holder is supported in its upright position, illustrated in Fig. 11, by lateral extensions 167 of brackets 166, said extensions projecting toward each other in

position below the bottom of the pin holder which rest on the top edges of said extensions. The pivotal movement of pin holder 48A and the movement of plate 168 for carrying said pin holder toward the pin carrier holder 10A is accomplished in the manner which will now be described. For this purpose, pin holder 48 is provided with an integral cam portion 174 at the pivoted edge 162 thereof. As clearly shown in Fig. 14, cam portion 174 has a peripheral cam edge 175. An end portion 176 of a flexible cable or cord 178 engages said crank cam 174 in a groove 180 formed in said cam edge 175 and passes from one side of said pin holder through an opening 182 (Fig. 11) to the other side of said pin holder at which said end of cable 178 is secured as indicated at 186 in Fig. 12. Cable 178 passes around a pulley 192 mounted for rotation in a bracket 190 fixed to and upstanding from slidable plate 168. Said cable passes under card holder 10A and is fixed to a pulley 192 which is carried by a shaft 194 journaled for turning movement in bearings 196 fixed to the table or bench 64A.

It will be understood that when pulley 192 is turned in a clockwise direction viewing Fig. 12, pin holder 48A is pivotally moved in a clockwise direction by the pull of cable 178 on said pin holder, and on the crank cam 174 thereof, whereby said pin holder is first moved from the position illustrated in Fig. 28 to the position illustrated in Fig. 29, and thereafter from the position illustrated in Fig. 29 to the position illustrated in Fig. 30 for projecting the prongs of the pins through the pin carrier in the pin carrier holder 10A. The movement of pin holder 48A from the position illustrated in Fig. 28 to the position illustrated in Fig. 30 is continuous and is accomplished by a continuous turning movement of pulley 192 through a predetermined angular distance in said clockwise direction. It will be noted that when pin holder 48A is moved from the position illustrated in Fig. 28 to the position illustrated in Fig. 29, the pin holder 48A engages the top of the pin carrier 10A so that further rotary turning movement of the pin holder 48A in the same direction is thereby prevented, and that when this occurs, the force transmitted by pulley 192 to cable 178 acts on bracket 190, through pulley 188, for moving plate 168 and pin 48A carried thereby toward the pin-carrier holder 10A which is mounted in fixed position on top of bench 64A. A tension spring 198 is connected to plate 168 and to the base or mounting plate 62A, on which plate 168 is slidably mounted, for resiliently opposing movement of said plate toward pin-carrier holder 10A and for retracting said plate and the pin holder 48A, carried thereby when cable 178 is relaxed. It will be understood that movement of plate 168 for moving pin holder 48A toward pin-carrier holder 10A is prevented by the force of spring 198 and by friction of the parts until the pivotal movement of pin holder 48A by cable 178 is completed for bringing said pin holder to the position illustrated in Fig. 29 preliminary to the projection of the prongs of the pins through the pin carrier or card C in the pin-carrier holder 10A.

Pulley 192 is preferably automatically operated by power actuated means. More particularly, in accordance with the present invention, power for operating pulley 192 is transmitted thereto under the control of a one-revolution clutch 200, (Figs. 11 and 12A) having a stationary frame 201 which is fixed to the under side of bench 64A. Said one-revolution clutch comprises a driving clutch

member 202, having a plurality of peripherally spaced jaws 204, and a driven clutch member 206 which has similarly peripherally spaced jaws 208, which engage driving clutch member 202 in the recesses between the jaws 204 thereof. Driving clutch member 202 is fixed to a rotary shaft 210 which is operated by a sprocket wheel 212 actuated by a sprocket chain 214. Said shaft 210 is journaled for rotation in a bearing 215. A sprocket wheel 216 is connected to sprocket chain 214 for actuating the same, said sprocket wheel 216 being rotated by a gear-reduction mechanism 218 operated by a motor (not shown) which is connected in any suitable way to the driving pulley 220. It will be understood that during the operation of the apparatus, shaft 210 of the one-revolution clutch 200 is in constant rotation for constantly rotating the driving clutch member 202. The driven clutch member 206 is slidably mounted on the driven shaft 222, but is held against rotation on said shaft. Shaft 222 is journaled for rotation in a bearing 223. A compression spring 224 surrounds shaft 222 and bears at one end thereof against the adjacent end of said shaft bearing 223 which is mounted in part 226 of the clutch frame 201, the opposite end of said spring bearing against said driven clutch member 206. A clutch control member 228 is pivoted on the frame of the clutch by a pivot pin 230. Said control member 228 is provided with a cam portion 232 which is fixed to and extends transversely between the arms 233 of control member 228 and which is engageable by a pin 234 fixed to and projecting radially from the driven clutch member 206. When pin 234 is in engagement with cam 232 of control member 228, at the portion of said cam member which is nearer the pivot 230, the driven clutch member 206 is in retracted position out of engagement with the driving clutch member 202 and driven shaft 222 is stationary. When the clutch control member 228 is moved in a clockwise direction (viewing Fig. 12A) for releasing pin 234 from cam 232, spring 224 moves the driven clutch member 206 into engagement with the rotating driving clutch member 202, whereby driving shaft 210 is connected to shaft 222 for rotating the latter.

Clutch control member 228 is manually operated by a treadle 236 connected to said clutch control member by a link 238 (Fig. 12). One or more tension springs 240 are connected to clutch control member 228 for holding the latter in position to be engaged by pin 234 of the driven clutch member. It will be understood that during part of the rotation of driven clutch member 206, pin 234 engages cam 232 of the clutch control member 228 and that when said pin approaches the part of the cam which is nearest to the frame part 226 of the clutch, the driven clutch member 206 is disengaged from the driving clutch member 202 and the rotation of shaft 222 is interrupted. The driven shaft 222 is provided with a crank arm 242 which is connected by means of a link 244 to a crank arm 246 fixed to shaft 194 for turning pulley 192. It will be understood that shaft 222 makes one revolution under the control of the one-revolution clutch 200 and that pulley 192 is oscillated but is not rotated during one complete revolution of shaft 222. More particularly, during one revolution of shaft 222 pulley 192 is first turned in a clockwise direction viewing Fig. 12 through an angular distance necessary to move the pin holder 48A from the position illustrated in Fig. 28 to the position

illustrated in Fig. 30, and then said pulley is turned in a counter-clockwise direction to relax the cable 178 and to provide sufficient slack therein to permit the pin holder 48A and the slideable plate 168 on which said pin holder is mounted to be returned by the tension spring 198 to the retracted position of said pin holder and plate illustrated in Figs. 11, 12 and 28. At the end of the movement of pulley 192 in it counter-clockwise direction for relaxing cable 178, the driven clutch member 206 is automatically disengaged from the driving clutch member 202 by the engagement of pin 234 with cam 232 of the clutch control member 228 as described above, and remains disengaged until said clutch control member 228 is again operated by treadle 236 to initiate the operation of said one-revolution clutch. While the mechanism as thus described or its equivalent is preferred for moving plate 168 and pin holder 48A to the projected position automatically in response to the operation of clutch 200 initiated by the manual control treadle 236, it is within the scope of the invention to omit said clutch and pulley 192 and to operate cable 178 directly in any suitable way as for example by extending said cable over a guide pulley and connecting said cable to a treadle in the manner described above with reference to cable 70 as illustrated in Fig. 7, instead of connecting cable 178 to said oscillating pulley 192. Also it will be understood that the clutch for operating pulley 192 can be eliminated while said pulley is retained and that in such case, pulley 192 can be operated by treadle 236 operatively connected thereto for example by connecting said treadle by a link to crank 246. In either case, however, it will be understood that cable 178 will operate in conjunction with pulley 188 and cam 174 for actuating plate 168 and pin holder 48A as hereinbefore described.

Provision is made for holding plate 168 releasably in its projected position to which it is moved by the rotation of pulley 192 in a clockwise direction as described above, whereby said plate and the pin holder 48A carried thereby are retained in said projected position thereof, during the movement of pulley 192 in the opposite direction for relaxing cable 178, for it is while pin holder 48A is in said projected position thereof that the pins which are projected through the pin carrier pursuant to said movement of the pin holder to its projected position are closed. For thus releasably holding plate 168 in its projected position, there is provided a latch member 248 which is pivoted to the under side of the bench by a pivot pin 250 and which is biased to plate latching position by a compression spring 252. Latch member 248 carries a latch finger 254 which projects through an opening 256 in a stationary mounting plate 62A and which is provided with an upper inclined edge 258 which is adapted to be engaged by the leading edge 260 of plate 168 which depresses said latch finger 254 to the lower surface of said plate and stresses spring 252 so that when the opening 256 in plate 168 registers with latch finger 254, the latter is projected into said opening, as illustrated in Fig. 30, and prevents movement of plate 168 to its retracted position while pulley 192 is being moved under the control of the one-revolution clutch in its counter-clockwise direction for relaxing the cable 178. Latch member 248 is also provided with a latch finger 264 which projects through an opening 266 in mounting plate 62A in position to be engaged by a member hereinafter to be described

for actuating latch member 248 to release latch member 254 from plate 168, after the pins are closed, to permit the spring 198 to move said plate and the pin holder carried thereby away from the pin-carrier holder 10A to the retracted position of said plate and pin holder.

While the pin holder is in the projected position thereof illustrated in Fig. 30 and while the plate 168 is latched in its projected position illustrated in said figure of the drawings, the pin holder 48A is operated in relation to the pin-carrier holder 10A for closing the pins which have been projected through the pin carrier or card mounted in said pin-carrier holder 10A during the movement of pin holder 48A from the position illustrated in Fig. 29 to the position illustrated in Fig. 30. The means for accomplishing this operation will now be described.

In order to close the pins, the pin holder 48A is moved downwardly about its pivot provided by the pin 164 toward the upper surface of the pin carrier or card through which the prongs of the pin are projected, i. e., from the position of said pin holder illustrated in Fig. 30 to the position illustrated in Fig. 32, and simultaneously with the downward pivotal movement of said pin holder 48A, the latter is moved longitudinally of pin 164 in order to displace the heads of the pins laterally of their companion prongs whereby to permit the downward movement of said heads in relation to said prongs by said downward pivotal movement of the pin holder. The means for moving the pin holder 48A downwardly about the pivot provided by pin 164 comprises, as here shown, a rotary cam 268 which makes one revolution under the control of a one-revolution clutch 270. Said one-revolution clutch 270 is in general similar to the one-revolution clutch 200 which as described above controls the operation of pulley 192 for moving the pin holder 48 to its projected position. The driving shaft 272 of clutch 270 is journaled for rotation in a bearing 273 and is connected by means of a coupling 274 and is constantly rotated by the gear reduction mechanism 218 (Fig. 11). The driving clutch member 276 is fixed to said shaft and is engageable with a driven clutch member 278 fixed to the driven shaft 280 to which the rotary cam 268 is secured. Driven shaft 280 is journaled for rotation in a bearing 281. The clutch members 276 and 278 have peripherally spaced jaws 282 and 283, respectively, which releasably engage each other in the spaces between said jaws, as described above in connection with clutch 200. Said jaws of the driving and driven clutch members are held releasably in engagement with each other by a compression spring 284 which bears at one end thereof against the adjacent end of bearing 281, which is fixed in the part 286 of the stationary clutch frame, and at its other end against the driven clutch member 278. In Fig. 11, the driven clutch member 278 is shown disengaged from the driving clutch member 276, while in Fig. 20 said clutch members are shown in engaged relation, whereby shaft 272 is operable to rotate the cam 268 carried by the shaft 280.

The engagement of clutch member 278 with clutch member 276 and the disengagement of said clutch member 278 from clutch member 276 is controlled by the clutch control device 288 which is pivotally mounted on the frame part 286 as indicated at 290 and by a pin 292 which is fixed to and projects radially from the driven clutch member 278. The clutch control device

288 comprises two laterally spaced arms 294 and 296 (Fig. 21) having fixed thereto at their outer ends a transverse cam member 298 which is engaged by pin 292 during a part of the revolution of driven shaft 280 for moving the clutch member 278 longitudinally of driven shaft 280 to retract said driven clutch member from engagement with the driving clutch member 276, it being understood that the driven clutch member 278 is mounted on shaft 280 so as to be slidable longitudinally thereof, but so as to be non-rotatable thereon. In order to permit the driven clutch member 278 to engage the driven clutch member 276, it is necessary to disengage the cam 298 from pin 292, and this is accomplished by the pivotal movement of arms 294 and 296 about the pivot 290, spring 280 being operative to project driven clutch member 278 into driven engagement with driven clutch member 276 when cam 298 is disengaged from pin 292. It will be understood that upon movement of cam 298 to its retracted position out of engagement with pin 292, the jaws 283 of driven clutch member 278 quickly enter the spaces between the jaws 282 of driving clutch member 276, since the latter is constantly rotating so as to bring the recesses between said jaws into alignment with the jaws 283 of the driven clutch member, thus to permit the spring 284 to move the driven clutch member 278 to its projected position for engagement in the recesses between the jaws of the driving clutch member.

The means for pivotally moving arms 294 and 296 and for controlling the movement of said arms for projecting and retracting cam 298 comprises a member 300 fixed to one end of arm 296, which as illustrated in Fig. 20, projects forwardly beyond the pivot 290. Member 300 projects downwardly and is provided with a bevelled lower portion 302 (Fig. 24) disposed in position to be engaged by the arm 304 of a control device 306 which is mounted on plate 168 (Figs. 11, 20 and 25). Control device 306 is mounted for pivotal movement in a plane parallel to the plane of plate 168 about a pivot pin 308 and is held against movement in one direction by a pin 310 which is fixed to and projects upwardly from plate 168. A tension spring 312 holds the control member 306 in its normal position in engagement with stop pin 310. As illustrated in Fig. 30, when the pin holder 48A is in its projected position, arm 304 is in engagement with the lower end portion 302 of member 300 for holding the clutch control cam 298 in its retracted position, and it will be understood that the movement of arm 294 of clutch control device 298 for thus retracting the cam 298 occurs during the latter part of the movement of plate 168 to its projected position, as may be observed by a comparison of Figs. 29 and 30, and that during this latter part of the movement of plate 168 to its projected position, arm 304 of control member 306 engages the bevelled edge portion 302 of member 300, whereby to turn arm 296 of clutch control device 298 in a clockwise direction viewing Fig. 20. Arm 304 remains in engagement with member 300 for holding the cam 298 in its retracted position while the rotary cam 268 which is operated under the control of the one-revolution clutch 270 for acting upon pin holder 48A to close the pins makes one revolution, in a counter-clockwise direction viewing Fig. 12, from the position illustrated in said figure of the drawing and in Fig. 29, through the positions illustrated in Figs. 31, 32 and 33, to the position illustrated in Fig. 34.

During the rotation of cam 268, from the position illustrated in Fig. 30 to the position illustrated in Fig. 32, pin holder 48A is pivotally moved downwardly and as indicated above. This movement is accomplished by cam edge portion 301 (Fig. 20A). Cam edge portion 303 is circular in respect to the axis of rotation of the cam and therefore does not operate to move pin holder 48A although it holds it down until it clears said pin holder. During the downward movement of the pin holder 48A, it is also moved longitudinally of pin 164, first against the force of spring 172 in one direction, and thereafter said pin holder is moved longitudinally of pin 164 in the opposite direction by said spring. The movement of pin holder 48A longitudinally of pin 164 against the force of spring 172 is accomplished by the engagement of a pin 314 fixed to pin holder 48A (Fig. 11) by a cam 316 shown more clearly in Figs. 11 and 20. More particularly, said cam is provided with a downwardly inclined upper surface 318 which engages the end of pin 314 and presses on the latter in a direction to move pin holder 48A longitudinally of pin 164 against the pressure of spring 172 during the downward pivotal movement of said pin holder. Upon the end of the downward pivotal movement of pin holder 48A, pin 314 passes downwardly beyond the adjacent end of inclined surface 318 of cam 316 so that said pin 314 is clear of said cam whereupon spring 172 is effective to move pin holder 48A longitudinally of pin 164 in a direction opposite to that in which said pin holder was moved by the engagement of pin 314 with said cam. Cam 316 is pivotally mounted on a pivot pin 320 for movement in a counter-clockwise direction (viewing Fig. 20) to allow the pin holder 48A to be moved from the inverted position thereof illustrated, for example, in Fig. 32 to the upright position thereof illustrated, for example, in Fig. 35. Downward movement of cam 316 about its pivot by pin 314 is prevented by the engagement of the lower surface of said cam with the upper surface of block 322 which is fixed to base 62A. It will be understood that after rotary cam 268 disengages the pin holder 48A, as illustrated, for example, in Fig. 33, following the downward, pivotal and longitudinal movements of said pin holder 48A, said pin holder is pivotally moved upwardly whereby the prongs of the pins are engaged in the companion heads thereof. This upward pivotal movement of pin holder 48A can occur after cam 268 disengages said pin holder because of the provision of slack in the cable 178A by the movement of pulley 192 in a counter-clockwise direction (viewing Fig. 12) which starts as described above as soon as pin holder 48A has been moved to its projected position.

At the end of the downward pivotal movement of pin holder 48A, illustrated in Fig. 32, control member 306 is actuated to engage latch finger 264 for operating latch member 248 whereby to release latch finger 264 from retaining engagement with plate 168 in order that said plate may be moved to its retracted position by spring 198 and thereby move said pin holder 48A to the retracted position thereof illustrated in Fig. 34. This movement of control member 306 for operating latch member 248 is effected by the engagement of cam edge 301 of rotary cam 268 with a pin 324 fixed to said control member 306. The engagement of rotary cam 268 with pin 324 for actuating latch member 248 to release plate 168 is illustrated in Figs. 32 and 33, and it will be understood that member 306 is moved by cam 268

against the force of spring 312 in a clockwise direction viewing Fig. 11, whereby to engage the upper inclined end 326 of latch-releasing finger 264 of latch member 248 for moving the latter from the position illustrated in Fig. 31 to the position illustrated in Figs. 32 and 33. It will be noted, however, that until the circular edge 303 of rotary cam 268 disengages pin 324, plate 168 and the pin holder 48A are prevented from moving to retracted position, but that as soon as circular edge 303 of cam 268 disengages pin 324, plate 168 and the pin holder 48A carried thereby are quickly moved by spring 198 to the retracted position illustrated in Fig. 34 in which position the edge 328 of plate 168 engages the stop pins 330 which are fixed to and project upwardly from the mounting plate 62A. In the movement of arm 304 to engage latch finger 264 for actuating latch member 248 to release plate 168, the end 329 of said arm rides over the bevelled end portion 302 of member 300 and clears the same so that control device 288 can return to a position for engagement by pin 292 of the driven clutch member 278 to disengage the latter from driving clutch member 276 at the end of one revolution of cam 268. It will be noted that the return of arm 304 from latch releasing position to normal position in engagement with stop pin 310 occurs during the movement of plate 168 to its retracted position and that during said return of arm 304 the latter clears member 300 which engages side 339 of said arm and moves said arm pivotally against the action of spring 312. As soon as arm 304 clears member 300, spring 312 returns said arm to the position illustrated in full lines in Fig. 25 to the extent allowed by stop pin 310. As soon as arm 304 of control member 306 disengages latch-releasing finger 264, the spring 252 of latch member 248 operates to return said latch member to the position illustrated in Fig. 12 for engagement by arm 304 upon the next movement of plate 168 and the pin holder carried thereby to projected position.

After the pin holder 48A is moved to its retracted position illustrated in Fig. 34, the pin holder 48A is disengaged from the pin-carrier holder 10A and is moved from its inverted position illustrated in Fig. 34, to the upright or pin-receiving position illustrated in Fig. 35. This movement may be conveniently effected by a quick upward pivotal movement of the pin-carrier retaining member 24A of the pin-carrier holder 10A from the position illustrated in Fig. 34 to the position illustrated in Fig. 35. When the card-retaining member 24A is thus operated for pivotally moving pin holder 48A from its inverted to its upright or pin-receiving position, the pin carrier or part C carrying the pins mounted thereon is disengaged from the stationary forming member 14A of the pin carrier holder 10A, thus resulting in the quick removal of the pin carrier with the pins mounted thereon from the holder 10A for transfer by hand or in any suitable way to a collection receptacle.

The pin-carrier holder 10A is, in general, of the same construction as the pin-carrier holder 10 provided in the apparatus illustrated in Figs. 1 to 10, but pin-carrier holder 10A embodies certain advantageous features which will now be described with reference to Figs. 11 and 16 to 19 inclusive. As here shown, the grooves 22A in the convex upper surface of the stationary forming member 14A taper in width from the side bar 36A of the pin-carrier retaining member 24A to the other side bar 28A of said retaining member.

Also, as illustrated in Fig. 17, the bottoms 22' of the grooves 22A are inclined upwardly in a direction extending from bar 36A to bar 28A. Also the grooves 38A in side bar 36A are wider than the grooves 40A in side bar 28A, said grooves 38A being in alignment with and of the same width as grooves 22A. Also, as shown in Fig. 17, the bottoms of grooves 38A are in line with the adjacent ends of the bottoms of grooves 22A while the grooves 40A in side bar 28A extend below the bottom of the adjacent ends of grooves 22A. By reason of the narrow width of groove 22A adjacent one end thereof while the groove is substantially wider at its opposite end, bending of the pin in such manner as to substantially deform the same during the longitudinal movement of the pin holder 48A on mounting pin 164 for closing the pins after they are projected through the pin carrier or card C is prevented, since the prongs of the pins are held against lateral movement only in the narrow ends of the grooves 22A while a substantial part of the prong of the pin can move laterally of said grooves with the movement of the heads of the pins and the side wires thereof which are held in the companion receptacles of the pin holder 48A. Also, by reason of the upward inclination of grooves 22A from the inlet ends thereof toward the ends through which the free ends of the prongs project, only the part of the prong between the ends thereof engages the bottom of the groove during the movement of the pin holder longitudinally of mounting pin 164.

The operation of the apparatus illustrated in Figs. 11 to 35 is believed to be apparent from the above description and therefore a detailed description of said operation is unnecessary. However, a brief summary of the operation of the apparatus will be helpful and therefore will now be given with more particular reference to Figs. 26 to 35. First, with the pin holder 48A in its upright position, closed safety pins P are mounted in the pin holder 48A as illustrated in Fig. 26 and as described above with reference to the pin holder 48 of the apparatus illustrated in Figs. 1 to 11. Then, the treadle 130 is depressed to operate the prong-releasing member 106 for opening the pins, as illustrated in Figs. 27 and 28, and as described above with reference to the apparatus illustrated in Figs. 1 to 10. Then the treadle 236 (Figs. 11 and 12) is momentarily depressed for retracting the clutch control member 228, thus initiating the operation of the one-revolution clutch 200 to make one revolution whereby to turn the pulley 192 whereby first to move the pin holder 48A from the upright position thereof illustrated in Fig. 28 to the inverted position thereof illustrated in Fig. 29, and thereafter to move plate 168 and pin holder 48A from the retracted position illustrated in Fig. 29 to the projected position illustrated in Fig. 30 which results in the projection of the prongs of the pins through the pin carrier or card in the pin-carrier holder 10A. As soon as the plate 168 reaches the projected position thereof illustrated in Fig. 30, the latch member 248 is operated, as described above, to engage the latch finger 254 thereof with plate 168 to retain said plate and the pin holder 48A thereof in projected position. During the movement of plate 168 to its projected position, pulley 192 turns through a predetermined angular distance in one direction, and after said plate 168 is thereby moved to its projected position, said pulley turns in the opposite direction so as to relax the cable 178 and to provide slack therein, thus enabling plate 168 and

the pin holder 48A carried thereby to be moved by spring 198 to the retracted position when such movement is subsequently allowed, following the closing of the pins, by the release of latch finger 254 from plate 168 and by the disengagement of cam 268 from pin 324 of control member 306. After the pin holder is moved to the projected position thereof illustrated in Fig. 30, it is operated upon by the rotary cam 268 for imparting thereto the above described downward pivotal and longitudinal movements for closing the pins, the prongs of which have been projected through the pin carrier during the movement of the pin holder from the position illustrated in Fig. 29 to the projected position illustrated in Fig. 30. Rotary cam 268 makes one revolution under the control of the one-revolution clutch 270 which is initiated by the engagement of the end 329 of arm 304 of control member 306 with the lower cam-edge portion 302 of member 300 for operating clutch-control device 288 to retract cam 298 of said control device 288 from engagement with the pin 292 which is carried by the driven clutch member 278. The movement of cam 268 during said one revolution thereof is illustrated in several stages in Figs. 30 and 34. Also, as explained above, during the downward pivotal movement of pin holder 48A by cam 268, said pin holder is moved longitudinally of pin 164, first in one direction by the engagement of cam 316 with pin 314 followed by the movement of pin holder 48A longitudinally of pin 164 in the opposite direction by spring 172 when said pin 314 clears the adjacent end of cam 316 during the downward movement of pin holder 48A. As the rotary cam 268 moves from the position illustrated in Fig. 31 to the position illustrated in Fig. 32, it engages the pin 302 of control member 306 and moves arm 304 thereof for actuating the latch member 248 to release the latch finger 254 from plate 168, and as soon as rotary cam 268 clears pin 324, which occurs shortly after the position of the parts illustrated in Fig. 33, the plate 168 and the pin holder 48A is moved by spring 198 to the retracted position illustrated in Fig. 34. Finally, the pin-carrier retaining member 24A is operated as described above for moving the pin holder 48A from the inverted position illustrated in Fig. 34 to the upright or pin-receiving position thereof illustrated in Fig. 35, and the pin carrier or card C having the pins P mounted thereon is removed from the pin-carrier holder and transferred to any suitable collection receptacle.

It will be understood that various changes may be made in the apparatus illustrated or described herein without departing from the underlying ideas of the present invention. Accordingly, I do not wish to be limited to the invention as herein shown or described.

Having thus described my invention and illustrated its use, what I claim as new and desire to secure by Letters Patent, is:

1. In apparatus for mounting a plurality of safety pins on a carrier formed of sheet material, said apparatus comprising means for holding said carrier in bent form, and a holder for a plurality of safety pins mounted for movement toward and away from said pin-carrier holder from a retracted position to a projected position over the surface of said carrier, for projecting the prongs of said pins through said carrier, means for moving said pin-holder to said projected position thereof, said holder being also mounted for movement toward and away from said surface

while said holder is in said projected position and for movement in a direction running transversely of the prongs of the pins for closing said pins after they are projected through said carrier, and means operable automatically in response to a predetermined movement of said holder to said projected position for imparting said movements to said holder for closing the pins.

2. In apparatus for mounting a plurality of safety pins on a carrier formed of sheet material, said apparatus comprising means for holding said carrier in bent form, and a holder for a plurality of safety pins mounted for movement toward and away from said pin-carrier holder from a retracted position to a projected position over the surface of said carrier, for projecting the prongs of said pins through said carrier, means for moving said pin-holder to said projected position, power-driven actuating means, means operable to connect said moving-means to and to disconnect the same from said power-driven actuating means, and means operable automatically to actuate said last mentioned means to disconnect said moving means from said actuating means when said pin-holder reaches said projected position thereof.

3. In apparatus for mounting a plurality of safety pins on a carrier formed of sheet material, said apparatus comprising means for holding said carrier in bent form, and a holder for a plurality of safety pins mounted for movement toward and away from said pin-carrier holder from a retracted position to a projected position over the surface of said carrier, for projecting the prongs of said pins through said carrier, means for moving said pin-holder to said projected position, power-driven actuating means, means operable to connect said moving-means to and to disconnect the same from said power-driven actuating means, manually operable means to initiate the action of said last mentioned means to connect said actuating means to said moving means, and means operable automatically to actuate said connect and disconnect means to disconnect said moving means from said actuating means when said pin-holder reaches said projected position thereof.

4. In apparatus for mounting a plurality of safety pins on a carrier formed of sheet material, said apparatus comprising means for holding said carrier in bent form, and a holder for a plurality of safety pins mounted for movement toward and away from said pin-carrier holder from a retracted position to a projected position over the surface of said carrier, for projecting the prongs of said pins through said carrier, means for moving said pin-holder to said projected position, power-driven actuating means, means operable to connect said moving-means to and to disconnect the same from said power-driven actuating means, means operable automatically to actuate said last mentioned means to disconnect said moving means from said actuating means when said pin-holder reaches said projected position thereof, and means operable in response to the movement of said pin-holding means to said projected position for releasably retaining the latter in said projected position.

5. In apparatus for mounting a plurality of safety pins on a carrier formed of sheet material, said apparatus comprising means for holding said carrier in bent form, and a holder for a plurality of safety pins mounted for movement toward and away from said pin-carrier holder from a retracted position to a projected position

over the surface of said carrier, for projecting the prongs of said pins through said carrier, means for moving said pin-holder to said projected position, power-driven actuating means, means operable to connect said moving means to and to disconnect the same from said power-driven actuating means, means operable automatically to actuate said last mentioned means to disconnect said moving means from said actuating means when said pin-holder reaches said projected position thereof, said holder being also mounted for movement toward and away from said surface while said holder is in said projected position and for movement in a direction running transversely of the prongs of the pins for closing said pins after they are projected through said carrier, and means operable automatically in response to a predetermined movement of said holder to said projected position for imparting said movements to said holder for closing the pins.

6. In apparatus for mounting a plurality of safety pins on a carrier formed of sheet material, said apparatus comprising means for holding said carrier in bent form, and a holder for a plurality of safety pins mounted for movement toward and away from said pin-carrier holder from a retracted position to a projected position over the surface of said carrier, for projecting the prongs of said pins through said carrier, means for moving said pin-holder to said projected position, power-driven actuating means, means operable to connect said moving-means to and to disconnect the same from said power-driven actuating means, manually operable means to initiate the action of said last mentioned means to connect said actuating means to said moving means, and means operable automatically to actuate said last mentioned means to disconnect said moving means from said actuating means when said pin-holder reaches said projected position thereof, said holder being also mounted for movement toward and away from said surface while said holder is in said projected position and for movement in a direction running transversely of the prongs of the pins for closing said pins after they are projected through said carrier, and means operable automatically in response to a predetermined movement of said holder to said projected position for imparting said movements to said holder for closing the pins.

7. In apparatus for mounting a plurality of safety pins on a carrier formed of sheet material, said apparatus comprising means for holding said carrier in bent form, and a holder for a plurality of safety pins mounted for movement toward and away from said pin-carrier holder from a retracted position to a projected position over the surface of said carrier, for projecting the prongs of said pins through said carrier, said pin-holder being mounted for movement in relation to said pin-carrier holder for closing the pins after they are projected through said carrier, and means operable upon said pin-holder in the projected position thereof for imparting said pin-closing movement to said pin-holder, means for actuating said last-mentioned means, and means movable with said pin-holder to said projected position for controlling the operation of said actuating means.

8. In apparatus for mounting a plurality of safety pins on a carrier formed of sheet material, said apparatus comprising means for holding said carrier in bent form, and a holder for a

plurality of safety pins mounted for movement toward and away from said pin-carrier holder from a retracted position to a projected position over the surface of said carrier, for projecting the prongs of said pins through said carrier, said pin-holder being mounted for movement in relation to said pin-carrier holder for closing the pins after they are projected through said carrier, and means operable upon said pin-holder in the projected position thereof for imparting said pin-closing movement to said pin-holder, means for actuating said last-mentioned means, and means automatically operable in response to the movement of said pin-holder to said projected position for initiating the operation of said actuating means.

9. In apparatus for mounting a plurality of safety pins on a carrier formed of sheet material, said apparatus comprising means for holding said carrier in bent form, and a holder for a plurality of safety pins mounted for movement toward and away from said pin-carrier holder from a retracted position to a projected position over the surface of said carrier, for projecting the prongs of said pins through said carrier, said pin-holder being mounted for movement in relation to said pin-carrier holder for closing the pins after they are projected through said carrier, and means operable upon said pin-holder in the projected position thereof for imparting said pin-closing movement to said pin-holder, means for actuating said last mentioned means and means automatically operable in response to the movement of said pin-holder to said projected position for initiating the operation of said actuating means, and means operable in response to a predetermined operation of said actuating means to interrupt the operation thereof.

10. In apparatus for mounting a plurality of safety pins on a carrier formed of sheet material, said apparatus comprising means for holding said carrier in bent form, and a holder for a plurality of safety pins mounted for movement toward and away from said pin carrier holder from a retracted position to a projected position over the surface of said carrier, for projecting the prongs of said pins through said carrier, means for moving said pin-holder to said projected position, power-driven actuating means, means operable to connect said moving-means to and to disconnect the same from said power-driven actuating means, means operable automatically to actuate said last mentioned means to disconnect said moving means from said actuating means when said pin-holder reaches said projected position thereof, means operable in response to the movement of said pin-holding means to said projected position for releasably retaining the latter in said projected position, said holder being also mounted for movement toward and away from said surface while said holder is in said projected position and for movement in a direction running transversely of the prongs of the pins for closing said pins after they are projected through said carrier, means operable automatically in response to a predetermined movement of said holder to said projected position for imparting said movements to said holder for closing the pins, and means automatically operable at the end of said pin-closing movements of the holder to release said retaining means.

11. In apparatus for mounting a plurality of safety pins on a carrier formed of sheet material, said apparatus comprising means for hold-

ing said carrier in bent form, and a holder for a plurality of safety pins mounted for movement toward and away from said pin carrier holder from a retracted position to a projected position over the surface of said carrier, for projecting the prongs of said pins through said carrier, means for moving said pin-holder to said projected position, power-driven actuating means, means operable to connect said moving-means to and to disconnect the same from said power-driven actuating means, means operable automatically to actuate said last mentioned means to disconnect said moving means from said actuating means when said pin-holder reaches said projected position thereof, means operable in response to the movement of said pin-holding means to said projected position for releasably retaining the latter in said projected position, said holder being also mounted for movement toward and away from said surface while said holder is in said projected position and for movement in a direction running transversely of the prongs of the pins for closing said pins after they are projected through said carrier, means operable automatically in response to a predetermined movement of said holder to said projected position for imparting said movements to said holder for closing the pins, means automatically operable at the end of said pin-closing movements of the holder to release said retaining means, said moving means being actuated to permit said pin-holder to move from said projected position to said retracted position when released by said retaining means, and means automatically operable to move said pin holder to said retracted position upon release of said retaining means.

12. In apparatus for attaching a plurality of safety pins to a carrier formed of sheet material and which comprises means for holding said carrier with an intermediate portion thereof displaced from the planes of laterally adjacent portions of said carrier, means for holding a plurality of said pins in spaced relation corresponding to the spaced relation which the pins are to have when attached to said carrier, said pin-holder being mounted for movement from a pin-receiving position to a position in which the prongs of the pins, disengaged from the companion heads of the pins, point toward said carrier in positions to project through said carrier at one side of said intermediate portion of the carrier, said pin-holder being also movable from a retracted position spaced from said carrier-holding means to a projected position for projecting the prongs of said pins through the carrier in said holding means, said carrier-holding means having means for holding the prongs of the pins in laterally spaced relation, said pin holder being also mounted for movement toward said prongs and laterally of said prongs successively, in two directions, while said prongs are held by said holding means for engaging the heads of the pins with their companion prongs for closing the pins after said prongs are projected through said carrier in said holding means.

13. In apparatus for attaching a plurality of safety pins to a carrier formed of sheet material and which comprises means for holding said carrier with an intermediate portion thereof displaced from the planes of laterally adjacent portions of said carrier, means for holding a plurality of said pins in spaced relation corresponding to the spaced relation which the pins are to have when attached to said carrier, said

pin-holder being mounted for movement from a position in which the prongs of the pins, disengaged from the companion heads of the pins, point toward said carrier in said holding means in positions to project through the carrier in said holding means at one side of said intermediate portion of the carrier to a projected position for projecting the prongs of said pins through that carrier in said holding means, said carrier-holding means having means for holding the prongs of the pins in laterally spaced relation, said pin holder being also mounted for movement toward said prongs and laterally of said prongs successively in two directions, while said prongs are held by said holding means, for engaging the heads of the pins with their companion prongs for closing the pins after said prongs are projected through said carrier in said holding means, power means operable in response to the movement of said pin-holder to said projected position thereof for moving said holder toward said prongs, and means operable during said last movement of said pin-holder toward said prongs to move said holder laterally of said prongs successively in said two directions.

14. In apparatus for attaching a plurality of safety pins to a carrier formed of sheet material and which comprises means for holding said carrier with an intermediate portion thereof displaced from the planes of laterally adjacent portions of said carrier, means for holding a plurality of said pins in spaced relation corresponding to the spaced relation which the pins are to have when attached to said carrier, said pin-holder being mounted for movement from a position in which the prongs of the pins, disengaged from the companion heads of the pins, point toward said carrier in said holding means in positions to project through the carrier in said holding means at one side of said intermediate portion of the carrier to a projected position for projecting the prongs of said pins through the carrier in said holding means, said carrier-holding means having means for holding the prongs of the pins in laterally spaced relation, said pin holder being also mounted for pivotal movement toward said prongs and laterally of said prongs successively in two directions, while said prongs are held by said holding means, for engaging the heads of the pins with their companion prongs for closing the pins after said prongs are projected through said carrier in said holding means, a cam engageable with said pin-holder in said projected position thereof for pivotally moving said pin-holder toward said prongs, means releasably engageable with said pin-holder in said projected position and operable in response to a part of said pivotal movement of said pin holder for moving the same in one of said directions laterally of the prongs of the pins, and means automatically operable in response to an additional part of said pivotal movement of said pin-holder for moving said pin holder in the other of said directions.

15. In apparatus of the character described, a pin-holder, means mounting said pin-holder for pivotal movement, said pin-holder having a cam in fixed relation thereto, said cam projecting radially of the pivotal axis of said pin-holder and forming a crank for turning said pin-holder about said axis, said cam having a peripheral cam edge spaced radially from said pivotal axis, and a flexible cable attached to said pin-holder at one side of said pivotal axis thereof and extending over said peripheral edge of said cam in

releasable bearing relation thereto for turning said pin-holder about said pivotal axis.

16. In apparatus of the character described, means mounted for sliding movement in two directions, a pin-holder carried by said slidable means and movable as a unit therewith, said pin-holder being also mounted for pivotal movement, and means operable to pivotally move said pin-holder and to automatically move said slidable means in one direction after a predetermined pivotal movement of pin-holder, said last mentioned means comprising a cam in fixed relation to said pin holder, said cam projecting radially of the pivotal axis of said pin-holder and having a peripheral cam-edge spaced radially from said pivotal axis, a pulley carried by said slidable means for rotation about an axis spaced from said pivotal axis of the pin holder, a flexible cable attached to said pin-holder at one side of said pivotal axis and extending over said cam-edge in releasable bearing relation thereto for turning said pin-holder about said pivotal axis in a direction running toward one of the directions of movement of said slidable means, said cable passing from said cam to said pulley in a direction opposite to said one of the directions of movement of said slidable means, over said pulley, and then in said one direction, means for opposing movement of said slidable means in said one direction whereby when the cable is pulled in said one direction the pin-holder is first pivotally moved to a predetermined position, and means opposing pivotal movement of said pin-holder beyond said predetermined position whereby continued pulling of said cable in said one direction is effective to move said slidable means and said pin-holder as a unit in said one direction.

17. In apparatus for mounting pins on cards, a card-holder, means mounted for sliding movement in two directions, toward and away from said card-holder, a pin-holder carried by said slidable means and movable as a unit therewith, said pin-holder being also mounted for pivotal movement, means for applying a force in one direction for pivotally moving said pin-holder to a predetermined position located in one direction of movement of said slidable means, means for opposing movement of said slidable means while said pin-holder is pivotally moved to said predetermined position, and means for opposing further pivotal movement of said pin-holder beyond said predetermined position whereby continued application of said force in the same direction is effective to move said slidable means and said pin-holder as a unit in said one direction.

18. In apparatus for attaching a plurality of safety pins to a carrier formed of sheet material, means for holding said carrier in position, means movable toward and away from said carrier-holding means from a retracted position to a projected position and return to said retracted position, a holder for a plurality of safety pins carried by said movable means and movable therewith for projecting the prongs of the pins through the carrier, said carrier-holder having means for guiding the prongs of the pins through the carrier in said carrier holder and for holding said prongs in position laterally of each other, said pin holder being also mounted for movement to move the heads of the pins toward and laterally of the companion prongs of the pins for closing the pins after the said prongs are projected through the carrier in the carrier holder, means operable in the projected position of said

first mentioned movable means for moving said pin-holder to move the heads of the pins toward their companion prongs, and control means movable with said movable means for automatically initiating the operation of said pin-holder moving means when said movable means is in said projected position thereof.

19. In apparatus for attaching a plurality of safety pins to a carrier formed of sheet material, means for holding said carrier in position, means movable toward and away from said carrier-holding means from a retracted position to a projected position and return to said retracted position, a holder for a plurality of safety pins carried by said movable means and movable therewith for projecting the prongs of the pins through the carrier, said carrier-holder having means for guiding the prongs of the pins through the carrier in said carrier holder and for holding said prongs in position laterally of each other, said pin-holder being also mounted for movement to move the heads of the pins toward and laterally of the companion prongs of the pins for closing the pins after the said prongs are projected through the carrier in the carrier holder, a rotary cam engageable with said pin-holder in the projected position thereof for actuating said pin-holder to move the heads of pins toward their companion prongs, a one-revolution clutch for actuating said cam, said clutch including a control device therefor, and control means movable with said movable means for actuating said control device to initiate the operation of said clutch when said movable means is in said projected position thereof.

20. In apparatus for attaching a plurality of safety pins to a carrier formed of sheet material, means for holding said carrier in position, means movable toward and away from said carrier-holding means from a retracted position to a projected position and return to said retracted position, a holder for a plurality of safety pins carried by said movable means and movable therewith for projecting the prongs of the pins through the carrier, said carrier-holder having means for guiding the prongs of the pins through the carrier in said carrier holder and for holding said prongs in position laterally of each other, said pin-holder being also mounted for movement to move the heads of the pins toward and laterally of the companion prongs of the pins for closing the pins after the said prongs are projected through the carrier in the carrier holder, a rotary cam engageable with said pin-holder in the projected position thereof for actuating said pin-holder to move the heads of pins toward their companion prongs, a one-revolution clutch for actuating said cam, said clutch including a control device therefor, and control means movable with said movable means for actuating said control device to initiate the operation of said clutch when said movable means is in said projected position thereof.

21. In apparatus for attaching a plurality of safety pins to a carrier formed of sheet material, means for holding said carrier in position, means movable toward and away from said carrier-holding means from a retracted position to a projected position and return to said retracted position, a holder for a plurality of safety pins

carried by said movable means and movable therewith for projecting the prongs of the pins through the carrier, said carrier-holder having means for guiding the prongs of the pins through the carrier in said carrier holder and for holding said prongs in position laterally of each other, said pin-holder being also mounted for movement to move the heads of the pins toward and laterally of the companion prongs of the pins for closing the pins after the said prongs are projected through the carrier in the carrier holder, a rotary cam engageable with said pin-holder in the projected position thereof for actuating said pin-holder to move the heads of pins toward their companion prongs, a one-revolution clutch for actuating said cam, said clutch including a control device therefor, and control means movable with said movable means for actuating said control device to initiate the operation of said clutch when said movable means is in said projected position thereof, and a part in fixed relation to said control means operable by said cam for releasing said control device of said clutch after a predetermined movement of said pin-holder by said cam and before the completion of one revolution of said clutch, means for releasably retaining said movable means in said projected position thereof, means actuated by a part of said control member for releasing said retaining means, and means operable automatically upon the release of said retaining means to return said movable means to said retracted position.

22. In apparatus of the character described, a holder for a plurality of safety pins, said holder comprising a plurality of pin receptacles disposed laterally of each other, said receptacles being constructed and arranged to receive the pins with the prong and side wire of the pin in each receptacle disposed in a plane transversely of the bottom of the receptacle, and

means mounting said holder for movement from a position in which the bottoms of said receptacles are below the pins therein to a position in which the bottoms of said receptacles are above the pins therein, said holder being also mounted for movement from one position to another in a direction extending transversely of said plane, and means for yieldably opposing the movement of said holder to said last mentioned position.

23. In apparatus of the character described, a holder for a carrier formed of sheet material on which a plurality of safety pins are to be mounted in laterally spaced relation, said carrier holder comprising a forming member having a convex surface provided with a plurality of spaced grooves extending laterally of said member, said grooves forming spaces and guides for the prongs of the pins in the projection thereof through the carrier in said holder, said grooves tapering in width from the inlet ends towards the ends thereof toward which said prongs are moved in for projecting them through the carrier.

24. In apparatus of the character described, a holder for a carrier formed of sheet material on which a plurality of safety pins are to be mounted in laterally spaced relation, said carrier holder comprising a forming member having a convex surface provided with a plurality of spaced grooves extending laterally of said member, said grooves forming spaces and guides for the prongs of the pins in the projection thereof through the carrier in said holder, said grooves tapering in width from the inlet ends towards the ends thereof toward which said prongs are moved in for projecting them through the carrier, the bottom of said grooves being inclined upward from the inlet ends thereof toward the opposite ends thereof.

HARRY ALFANDRE.
